PRINTING MECHANISM

Worth G. Read, St. Paul, Minn.

Application December 1, 1939, Serial No. 307,109

6 Claims. (Cl. 101—377)

This invention relates to printing mechanism of the class having a flexible holder or galley adapted to be laid flat when removed from the supporting element of the press and to be bent to an arc conforming with the periphery of a cylindrical supporting segment, the device being an improvement upon the mechanisms described in my Patent No. 2,025,307, granted December 24, 1935, and No. 2,045,408, granted June 23, 1936, and in my co-pending application for patent on Printing mechanism, Serial No. 266,318, filed April 6, 1939.

It is an object of the present invention to provide novel means for quickly and easily consolidating and compressing individual line members transversely, said members and compressing means being movable longitudinally of a flexible holder or galley.

A particular object is to provide in mechanism of this class a flexible holder or galley having parallel flanges for engaging the ends of the line members and a multiplicity of perforations along the bend of each of such flanges for engagement with follower bars whereby the line members may be compressed quickly and easily and held in properly fixed position for high grade printing.

Another object is to provide, in mechanism having a flexible form holder and individual line members, a follower bar for consolidating the line members and means on the bar for positively engaging the form holder and for resiliently consolidating the line members on the holder.

Other objects will appear and be more fully pointed out in the following specification and claims.

Referring to the accompanying drawing:

Figure 1 is a plan view of my improved form holder, laid flat, with a number of line members mounted thereon and showing my improved follower bars partially in plan view and partially in horizontal section;

Fig. 2 is a cross section on a somewhat enlarged scale taken on the line 2—2 of Fig. 1, and

Fig. 3 is an enlarged, fragmentary, longitudinal section taken on the line 3—3 of Fig. 1.

In the drawing, the numeral 4 indicates a flexible form holder or galley constructed from thin sheet material. The side edges of this holder are parallel to each other and each has a flange 5 bent inwardly to slidably engage individual line members 6. The ends of these members 6 are formed with recesses 7 to receive the flanges 5 respectively. A multiplicity of small perforations 8 are formed in the holder 4 at the bend of each flange 5, these perforations being spaced

at regular intervals to receive pointed ends 9 on the follower bars 10. Each of the ends 9 of each bar 10 is integral with a movable head 11 mounted on a small rod 12 which is slidable in a longitudinal bore in the bar and pressed outward by a small compression spring 13 confined in the bore. Each bar has a pair of longitudinally elongated slots 14 at its outer side to guide manually operable pins 15 and 16 which are fixed at their inner ends respectively in the rods 12. The pins 15 and 16 for each follower bar 10 may be pressed toward each other to withdraw the ends 9 from engagement with the perforations 8 in the flanges 5.

15 A leaf spring 17 is fastened to each of the bars 10 to resiliently engage the adjacent line holder 6, each of these springs 17 engaging a line holder near both ends of the latter. A pair of thrust screws 18 are also threaded in each of the follower bars 10 to limit backward movement of the springs 17 and to positively compress the line holders in the form in cases where such compression is required. Individual type 20 are indicated in the line holder 6 shown in Fig. 2 and a few of such type are shown in one of the line holders in Fig. 1.

In use the individual type 20 are composed in the line holders 6 while the latter are removed from the form holder 4 and then the line holders are assembled on the form holder with the flanges 5 of the latter in engagement with the ends of the line holders in recesses 7. It will be understood that at least one of the follower bars 10 is removed from the form holder while the line holders are placed in engagement with the form holder and when the composition of the entire galley has been completed the follower bar 10 is replaced and secured with the ends 9 in opposite perforations 8 in the form holder.

40 During the adjustment of the follower bars away from the line holders the pins 15 and 16 are pressed toward each other to compress the spring 13 and retract the ends 9 so that they pass freely between the flanges 5. With the spring 13 released the follower bar may be moved toward the line holders until the springs 17 are compressed to the desired degree or until the ends of the screws 18 strike the line holders to compress them. During this compression movement 45 the spring 13 allows the pointed ends 9 to advance from one perforation 8 to another by a ratchet-like movement. This movement of the follower bars is facilitated by the formation of a bevel on the front face of each end 9, as shown in Fig. 1. With both bars 10 in place and the

springs 17 under compression, the form holder is ready to be mounted on the arcuate segment of the press. In most cases no further compression of the individual line members on the form by operation of the screws 18 is necessary. The form holder may be attached to the segment by mechanism such as that described in my Patent No. 2,045,408, or other suitable means.

The springs 17 are not essential although for some classes of work they may be caused to exert sufficient lateral pressure on the assembled line holders to automatically consolidate the lines when the flexible holder is bent from flat to arcuate position on the segment. Where higher compression is desirable the bars 10 are forcibly advanced toward each other or the thrust screws 18 may be tightened after the form holder is in place on the segment to positively compress the line holders together between the follower bars. When the form is to be unlocked, either after detachment from the segment or while in place thereon, the pins 15 and 16 are actuated to withdraw the pointed ends 9 from engagement with the perforations 8 in the holder 4.

Having described my invention, what I claim as new and desire to protect by Letters Patent is:

1. Printing mechanism having in combination a flexible form holder having a plate portion adapted to be mounted on the periphery of an arcuate segment and to be laid flat when removed therefrom, a multiplicity of individual line members extending in parallel relation to each other on said form holder, parallel flanges inwardly bent from opposed edges of said plate portion, said flanges slidably engaging the ends of and retaining said line members, a multiplicity of perforations along the bend of each of said flanges, a follower bar extending substantially parallel to said line members on the form holder and toothed means on said follower bar adapted to removably engage said form holder in said perforations for consolidating said line members thereon.

2. Printing mechanism having in combination a flexible form holder having a plate portion adapted to be mounted on the periphery of an arcuate segment and to be laid flat when removed therefrom, a multiplicity of individual line members extending in parallel relation to each other on said form holder, parallel flanges inwardly bent from opposed edges of said plate portions, said flanges slidably engaging the ends of and retaining said line members, a multiplicity of perforations being formed along the bend of each of said flanges, follower bars extending substantially parallel to said line members at opposite sides of said line members on said holder, toothed means on said follower bars adapted to removably engage said form holder in said perforations to consolidate said line members between the follower bars, said toothed means at one end of each follower bar being spring-pressed to project into engagement with the perforations and means for manually retracting said toothed means from engagement with said perforations.

3. Printing mechanism having in combination a flexible form holder having a plate portion adapted to be mounted on the periphery of an arcuate segment and to be laid flat when removed therefrom, a multiplicity of individual line mem-

bers extending in parallel relation to each other on said form holder, parallel flanges inwardly bent from opposed edges of said plate portion, said flanges slidably engaging the ends of and retaining said line members, a multiplicity of recessed seats along the bend of each of said flanges, a follower bar extending substantially parallel to said line members on the form holder, and projections on said follower bar adapted to removably engage said form holder in said recessed seats for consolidating said line members thereon.

4. Printing mechanism having in combination a flexible form holder having a plate portion adapted to be mounted on the periphery of an arcuate segment and to be laid flat when removed therefrom, a multiplicity of individual line members extending in parallel relation to each other on said form holder, parallel flanges inwardly bent from opposed edges of said plate portion, said flanges slidably engaging the ends of and retaining said line members, a series of opposed stop members along the bend of each of said flanges, and a follower bar extending substantially parallel to said line members on the form holder and engaging opposed stop members for consolidating said line members on the form holder.

5. Printing mechanism having in combination a flexible form holder having a plate portion adapted to be mounted on the periphery of an arcuate segment and to be laid flat when removed therefrom, a multiplicity of individual line members extending in parallel relation to each other on said form holder, parallel flanges inwardly bent from opposed edges of said plate portion, said flanges slidably engaging the ends of and retaining said line members, a series of opposed stop members along the bend of each of said flanges, a follower bar extending substantially parallel to said line members on the form holder and engaging opposed stop members for consolidating said line members on the form holder, and means carried by said follower bar and interposed between said follower bar and line members to compress the line members and retain them in consolidated relation.

6. Printing mechanism having in combination a flexible form holder having a plate portion adapted to be mounted on the periphery of an arcuate segment and to be laid flat when removed therefrom, a multiplicity of individual line members extending in parallel relation to each other on said form holder, parallel flanges inwardly bent from opposed edges of said plate portion, said flanges slidably engaging the ends of and retaining said line members, a multiplicity of recessed seats along the bend of each of said flanges, a follower bar extending substantially parallel to said line members on the form holder, and projections on said follower bar adapted to removably engage said form holder in said recessed seats for consolidating said line members thereon, and spring means carried by said follower bar and interposed between said follower bar and line members to resiliently compress the line members and retain them in consolidated relation.
